JP 2001-171702 6/2001

Primary Examiner—Susan Bennett Hattan

(74) Attorney, Agent, or Firm—Ryan Kromholz & Manion, S.C.

(57) **CLAIM**

The ornamental design for a bottle cap, as shown and described.

DESCRIPTION

FIG. 1 is a top perspective view;

FIG. 2 is a bottom perspective view;

FIG. 3 is a front elevation view; the rear elevation view being a mirror image thereof;

FIG. 4 is a left side elevation view, the right side elevation view being a mirror image thereof;

FIG. 5 is a top plan view; and,

FIG. 6 is a bottom plan view.

The broken line showing of internal threads in FIGS. 2 and 6 is included for the purpose of illustrating environmental structure and forms no part of the claimed design.

1 Claim, 3 Drawing Sheets# US D621,705 S
